UNITED STATES PATENT OFFICE.

HOMER LAUGHLIN, OF COLORADO SPRINGS, COLORADO.

METAL FURNITURE.

Application filed March 5, 1926. Serial No. 92,570.

This invention relates to metal furniture and more especially to a chair construction whereby all parts of the device can be made readily of metal, the structure being light, durable, and easily assembled.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

20 In said drawings,

Figure 1 is a side elevation of a rocking chair constructed in accordance with the present invention.

Figure 2 is a vertical section therethrough taken from front to rear.

Figure 3 is a section on line 3—3 Figure 1.

Figure 4 is a section on line 4—4 Figure 1.

30 Figure 5 is a section on line 5—5 Figure 2.

Figure 6 is a side elevation showing a slightly modified form of chair.

Referring to the figures by characters of reference 1 designates upwardly extending side strips of metal connected, at desired intervals, by cross strips 2 which can be riveted, welded or otherwise connected to the side strips. These strips 1 and 2 co-operate to form the back of the chair, the lower portions of the side strips 1 forming the rear legs 3. Ears 4 may be extended forwardly from the outer edges of these legs 3.

45 The front legs of the chair have been indicated at 5 and are formed of strips of metal, these legs being bolted or otherwise fastened to the sides of a metal frame 6 the rear portion of which is suitably attached to the legs 3. This frame 6 constitutes a brace for the chair.

The seat portion of the chair includes a metal frame 7 on which is arranged a plate 8 having downturned flanges 9 at the front and back thereof which lap and are secured to the front and back portions of the frame 7.

In the structure shown in Figures 1 to 5 inclusive the legs 3 and 5 are attached to rockers 10 each of which has an outwardly extending flange 11 along the lower or convex edge whereby a relatively broad tread is provided even though the rocker 10 is formed of a thin strip of metal. The ears 4 are bolted or otherwise attached to these rockers and the lower ends of the legs 5 are similarly connected to the rockers.

If it is desired to provide the chair with arms 12, the said arms can be formed by properly shaping a metal tube and forming the same with flattened ends bolted at proper points to the side strips 1 and to the upper ends of the legs 5. It is preferred to secure the forward end of these arms to the legs 5 by the same bolts 13 employed for attaching the frame 7 to the legs.

It is of course not necessary to provide a chair with arms and rockers but, instead, the same principles of construction can be utilized in the formation of a chair of the simple design shown in Figure 6 wherein the back strips 18' are connected by cross strips 14 and by the rear portions of superposed frames 15 and 16. The front legs 17 are also attached to these frames and the seat plate 18 is mounted on and secured to the frame 15 in the same manner as is the plate 8 heretofore described. Importance is attached to the fact that the flat faces of the strips 1 are disposed in planes substantially at right angles to the planes occupied by the flat faces of the front strips or legs 5. Thus when the strips 1 are connected by the cross strips 2 a flat back is provided which obviously is free to cushion the back of the occupant where such cushioning action could not be obtained by the use of angular back strips.

Obviously chairs of other designs can be constructed along the same lines and the arrangement of parts described permits considerable variation in the articles produced and at the same time avoids objectionable weight without sacrificing strength.

What is claimed is:

An all metal chair including superposed angular frames each formed of flat strip metal, a seat having downturned flanges at its edges lapping the upper frame at the front and back thereof, flat metal strips secured to the sides of the frames at the front thereof, flat metal strips secured to the backs of the frames at the sides thereof, the last mentioned strips

being extended above the seat, connections between the upwardly extended portions of said strips cooperating therewith to provide a chair back, tubular arms having flattened ends connected to the upwardly extending portions of the back strips and lapping the upper portions of the front strips, a single fastening means extending through the front portion of each arm, through the adjacent portion of the front leg strip and through the adjacent portion of the top frame, thereby to hold said parts tightly together, forwardly extending ears at the lower ends of

the back strips, rockers lapping and secured to the ears and the front strips, and a flange extending along the lower edge of each rocker and laterally therefrom, said flanges being exposed at the outer sides of the chair and constituting treads for the rockers, the back strips having their flat faces disposed in planes at right angles to the planes of the flat faces of the front strips. 15

In testimony that I claim the foregoing as my own, I have hereto affixed my signature. 20
